UNITED STATES PATENT OFFICE.

WILLIAM B. BROOKS, OF WATERBURY, CONNECTICUT, ASSIGNOR TO THE WATERBURY MANUFACTURING COMPANY, OF SAME PLACE.

SHAFT-TIP.

SPECIFICATION forming part of Letters Patent No. 340,091, dated April 20, 1886.

Application filed February 12, 1886. Serial No. 191,719. (No model.)

To all whom it may concern:

Be it known that I, WILLIAM B. BROOKS, residing at Waterbury, in the county of New Haven and State of Connecticut, have invented 5 certain new and useful Improvements in Shaft-Tips; and I do declare the following to be a full, clear, and exact description of the same, reference being had to the accompanying drawings, which form a part of this specification.

10 My invention relates to an improvement in shaft-tips; and it consists in a tip made of thin metal and having its open end bent outward for the abutment against it of the forward edge of the leather covering of the shaft.

15 My invention further consists in a tip made of thin metal, and having its open end thrown outward to form a hollow bead, against the outer edge of which the forward edge of the leather covering of the shaft abuts.

20 In the accompanying drawings, Figure 1 is a view in side elevation of the end of a shaft provided with my improved tip, and showing the abutment of the forward edge of the leather covering of the shaft against the outer edge of 25 a bead formed by throwing out the open end of the tip, and Fig. 2 is a view showing the tip and leather covering in longitudinal section.

As herein shown, the open end of the tip A is thrown out to form a hollow bead, B, 30 having its outer edge, C, turned inward to form the face D for the forward edge, F, of the leather covering of the shaft to abut against, the outer surface of the bead being knurled, and the tip being formed of light stock. The 35 outwardly bent or thrown portion of the tip should stand off from the shaft as much as or more than any of the thicknesses of leather ordinarily applied thereto, so that whatever may be the thickness of the leather within the 40 ordinary limits a good and neat fit may be secured between it and the tip by abutting its forward edge against the outwardly bent or thrown portion thereof without ever paring or skiving the leather, as is necessary with

ordinary tips when the edges of the same are 45 not as thick as the leather, such paring or skiving of the leather involving considerable labor and impairing its appearance and durability. Moreover, as the bending out of the end of the tip for the forward edge of the leather to abut 50 against makes the thickness of the stock in the tip immaterial to the fit between the tip and the leather, and as it greatly increases the strength and stiffness of the tip, the same may be made of lighter stock than it has been possible to use heretofore in shaft-tips, whereby 55 my invention secures a saving in stock and in the expense of working it. Furthermore, the facility with which my improved tip is applied, paring or skiving being done away with, makes 60 it a cheaper tip to use than the ordinary article.

I am aware that a shaft tip made of heavy metal cut away to form an interior chamber in its open end, adapting it to fit over the 65 leather, and having its forward edge beveled is not new. I do not, therefore, broadly claim a metallic shaft-tip adapted to protect the leather; but,

Having fully described my invention, what 70 I claim as new, and desire to secure by Letters Patent, is—

1. A shaft-tip made of thin metal, and having its open end bent outward for the forward edge of the leather covering of the shaft to 75 abut against, substantially as set forth.

2. A shaft-tip made of thin metal, and having its forward end thrown outward to form a bead, against the outer edge of which the forward edge of the leather covering of the shaft 80 abuts, substantially as set forth.

In testimony whereof I have signed this specification in the presence of two subscribing witnesses.

WM. B. BROOKS.
